UNITED STATES PATENT OFFICE.

JOSEPH HUSSONG, OF CAMDEN, NEW JERSEY.

DYEING-MACHINE.

SPECIFICATION forming part of Letters Patent No. 776,327, dated November 29, 1904.

Application filed May 7, 1903. Serial No. 156,118. (No model.)

To all whom it may concern:

Be it known that I, JOSEPH HUSSONG, a citizen of the United States, and a resident of Camden, New Jersey, have invented certain 5 Improvements in Dyeing-Machines, of which the following is a specification.

The object of my invention is to improve the construction of the frames on which are suspended the banks of yarn to be dyed in a 10 dyeing-machine, so that the sticks can be readily turned.

My invention is shown in connection with a dye-vat for which Letters Patent were granted to me the 9th day of April, 1901, No. 671,799; 15 but it will be understood that my invention can be used in connection with any suitable dye-vat.

In the accompanying drawings, Figure 1 is a longitudinal sectional view of a dye-vat, illustrating my improvement. Fig. 2 is a transverse sectional view on the line 22, Fig. 1. Fig. 3 is a sectional plan view of part of Fig. 1. Figs. 4 and 5 are perspective views of the carriers for the sticks, and Figs. 6 and 7 are 25 views of portions of Fig. 2 enlarged.

A is the dye-vat, having an end compartment *a*, in which is a circulating-wheel B, and under the compartment for the banks of yarn is a circulating-chamber *a'*, so that the dye 30 liquor is kept in constant circulation. The partition *b* is perforated, as shown. A plain vat may be used in some instances without departing from my invention.

D is the carrying-frame for the yarn. This 35 frame consists of side members D' D''. The side member D', as illustrated in Fig. 6, consists of two longitudinal bars *d d'*, secured together at intervals by bolts, while the side member D'' is a single frame. These two 40 frames have extensions *ee'*, which are coupled to longitudinal bars E E', which are in turn attached to cross-bars E'', and on these bars are eyes *e''*, with which engage the hooks *f*, carried by the chains F for raising the yarn-carrying frame out of the dye liquor.

Extending from one side member to the other is a partition G, having a series of perforations therein which allow the liquor to pass onto the upper portions of the banks of 45 yarn. The two longitudinal bars *d d'* are per-

forated at intervals and form the bearings for the worm-wheels I, which have extended hubs *i i*, mounted in the bearings in the longitudinal bars *d d'*, the teeth of the worm-wheels extending between the two bars, as illustrated 55 in Fig. 6.

Each worm-wheel is slotted at *i'* for the reception of the end of the sticks *n*, on which the banks of yarn are mounted, as illustrated clearly in Figs. 2 and 4.

H is a longitudinal shaft running the full length of the frame D and secured to the side member D' by bearings *h*. On this shaft are worms *h'*, which mesh with the worm-wheels I, as clearly illustrated in Fig. 1. One end 65 of the shaft is shaped to fit a suitable handle, so that when the yarn-frame is raised the handle can be applied to turn the shaft H, which will through the medium of the gearing turn the sticks.

It will be noticed that the worms are alternately arranged right and left, so that every other stick will turn in one direction, while the others will turn in the opposite direction.

The side member D'' is simply a single 75 frame, and mounted in this frame are disks J, each having a flange *j* at one side, and secured to the disk is a cap-plate *j''*, which holds the disk in position in the side member D'', as illustrated in Fig. 7. The disks are slotted at 80 *j'* to receive the ends of the sticks *n*. This construction makes a very simple and durable frame in which the sticks can be readily removed when it is desired to change a batch of yarn. It is comparatively light, and therefore can be readily raised and lowered, and the yarn-sticks, which are oblong in cross-section, as shown in Fig. 1, can be readily turned by simply raising the frame partly out of the vat, applying a handle to the end of the 85 shaft H, and turning it a half-turn, which will change the position of the yarn on the sticks and allow the entire bank to be evenly dyed.

I claim as my invention—

1. The combination in a frame for suspending hanks of yarn in a dye-vat, of two side members, a series of toothed wheels carried by one side member, and a series of revoluble disks having bearings carried by the other 100

side member, said wheels and disks being slotted to receive the respective ends of the yarn-sticks, substantially as described.

2. The combination in a yarn-frame for dyeing-machines, of the side members, a perforated partition carried by the side members and extending above the yarn, a series of wheels carried by one side member, revoluble disks having supporting-bearings carried by the other side member, said wheels and disks being slotted for the reception of the respective ends of the dye-sticks, and means for driving the wheels in unison, substantially as described.

15 3. The combination in a frame for suspending the hanks of yarn in a dye-vat, of the side members, one side member made up of two longitudinal perforated bars, a toothed wheel mounted between the bars and having flanges at each side entering the perforations in the bars and slotted to receive one end of a dye-stick, the other side member being a perforated single bar with a slotted disk mounted in the perforations of the bar, substantially as described.

20 4. The combination in a frame for suspending hanks of yarn in a dye-vat, of two side members, one side member being made up of two longitudinal perforated bars and the other side member being a single perforated bar, a

series of worm-wheels mounted between the bars of one side member and having flanges at each side entering the perforations in the bars, said worm-wheels being slotted to receive one end of the dye-stick, means for supporting the other end of the dye-stick in the other side member of the frame, a shaft, and a series of worms on the shaft meshing with the worm-wheels, substantially as described.

25 5. The combination in a yarn-frame for dyeing-machines, of the two side members, means for connecting the side members together, worm-wheels carried by one side member, disks carried by the other side member, a worm-shaft, bearings therefor, worms on the shaft meshing with the worm-wheels, the alternate worms being right-handed and the others being left-handed so that when the shaft is turned the alternate wheels will turn in opposite directions, said wheels and disks being slotted, with dye-sticks mounted in the slotted wheels and disks, substantially as described.

In testimony whereof I have signed my name to this specification in the presence of two subscribing witnesses.

JOSEPH HUSSONG.
